UNITED STATES PATENT OFFICE.

JOSEPH M. STRYHAL, OF WASHINGTON, DISTRICT OF COLUMBIA.

VALVE-GRINDING TOOL.

1,206,164.

Specification of Letters Patent. Patented Nov. 28, 1916.

Application filed July 28, 1916. Serial No. 111,885.

To all whom it may concern:

Be it known that I, JOSEPH M. STRYHAL, a citizen of the United States, residing at Washington, in the District of Columbia, have invented new and useful Improvements in Valve-Grinding Tools, of which the following is a specification.

This invention relates to valve grinding tools, the object in view being to produce a hand operated tool for imparting the necessary oscillatory movements to a valve to grind the same against the valve seat, said tool embodying in connection with a suitable stock or shank and handle, a valve engaging head shiftable or adapted to rock in relation to said stock or shank so as to maintain the proper engagement between the valve engaging head and the valve during the grinding operation.

20 A further object of the invention is to provide in connection therewith the valve engaging head and the shank or stock, yieldable means exerting a constant pressure against the valve engaging head and also 25 serving to yieldingly sustain the same in axial alinement with the shank or stock.

With the above and other objects in view, the invention consists in the novel construction, combination and arrangement, herein 30 fully described, illustrated and claimed.

In the accompanying drawing: Figure 1 is a side elevation of the valve grinding tool. Fig. 2 is a fragmentary side elevation thereof taken at a right angle to Fig. 1. Fig. 3 is 35 a fragmentary vertical section through the tool showing the relation between the shank and the valve engaging head. Fig. 4 is a cross section on the line 4-4 of Fig. 2.

The valve grinding tool contemplated in 40 this invention comprises a shank 1, the upper end portion of which is milled to form a hand grip 2. At the base of the milled portion or hand grip there is arranged a hand guard 3 in the form of an annular flange 45 to prevent the hands of the operator from moving downwardly as he oscillates the shank 1 by placing his hands upon opposite sides of the hand grip 2 and moving his hands alternately in opposite directions.

50 The lower end portion of the shank 1 is reduced in diameter as shown at 4 thereby forming a shoulder 5 for one extremity of a coiled expansion spring 6, the latter encircling the reduced portion 4 of the shank. A 55 washer 7 is preferably interposed between

the shoulder 5 and the adjacent end of the spring 6. Adjacent to its lower extremity the reduced portion 4 of the shank is formed with an opening 8 extending transversely thereto and having its opposite ends flared 60 or bell-shaped as shown in Figs. 3 and 4, said opening 8 receiving a pin 9 of less diameter than the opening 8, said pin 9 extending transversely through a valve engaging head 10 and serving to couple the head to 65 the shank.

The head 10 is formed with a bore or socket 11 to receive the reduced end portion 4 of the shank and said bore is of sufficiently larger diameter than the portion 4 of the 70 shank to admit of a rocking or wabbling motion of the head 10 in relation to the shank. The head 10 is also formed with a circular recess 12 to receive the lower extremity of the spring 6. Projecting from the bottom of 75 the head 10 is valve engaging means, the same being shown for convenience as consisting of a plurality of pins or bits 13 arranged in spaced relation to each other and adapted to engage corresponding pockets in 80 the valve body as will be readily understood by those familiar with the art to which this invention appertains.

From the foregoing description taken in connection with the accompanying drawings it will now be understood that the valve engaging head has a rocking or wabbling movement in relation to the shank and handle and therefor if the said shank and handle are not held in true axial alinement with 90 the head, the operation of the valve grinding tool will not be interfered with as the head may remain in perfect working engagement with the valve body. The spring exerts a pressure against the valve engaging 95 head so as to cause the pin 9 to normally bear against the bottom wall of the opening 8 but yields to permit the top wall of said opening to bear downwardly against the pin 9 thereby enabling any desired pressure to be 100 brought to bear against the head. Said spring also serves to center the shank in relation to the head or in other words said spring serves to yieldingly sustain the shank in axial alinement with the head thereby 105 greatly facilitating the grinding operation. Furthermore, by reason of the pin 9 being smaller than the opening 8, a limited amount of relative axial movement between the shank and head is permitted causing the 110

shank to give a quick start to the valve engaging head in case the valve should have a tendency to adhere to the valve seat.

I do not desire to be restricted to the details and proportions illustrated in the drawings, it being apparent that the valve grinding tool is susceptible of changes in the form, proportion and minor details of construction, which may accordingly be resorted to without departing from the principle or sacrificing any of the advantages of the invention.

I claim:

1. A valve grinding tool, comprising an operating shank, a valve engaging head having a socket in which the end portion of the shank is received, and a pin extending transversely through openings in said shank and head, said pin being fastened in one of said

members, and the opening in the other member being of considerably greater diameter than the pin to allow of a limited relative axial turning movement between the shank and head.

2. A valve grinding tool comprising, in combination, an operating shank formed with an opening extending transversely therethrough and having the ends thereof flared, a valve engaging head having a bore in which the end portion of the shank has a loose wobbling fit, a pin extending through said opening and of smaller diameter than said opening and serving to connect the head to the shank, and yieldable means between the head and shank.

In testimony whereof I affix my signature. 35

JOSEPH M. STRYHAL.
